United States Patent Office

Des. 200,484
Patented Mar. 2, 1965

200,484

PLATE OR SIMILAR ARTICLE

Wataru Uda, 2181 Central Road, Apt. A, Fort Lee, N.J.

Filed Jan. 7, 1964, Ser. No. 78,109

Term of patent 7 years

(Cl. D44—15)

The figure is a plan view of a plate or similar article showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
